LIFTING HANDLE FOR RAILROAD MOTOR CARS

Filed Nov. 13, 1928

George J. ErmentROUT,
By *D. A. Kelly*, Attorney

UNITED STATES PATENT OFFICE.

GEORGE J. ERMENTROUT, OF READING, PENNSYLVANIA.

LIFTING HANDLE FOR RAILROAD MOTOR CARS.

Application filed November 13, 1928. Serial No. 319,048.

This invention relates to improvements in handles for railway motor cars, and it is intended more particularly for use on a relatively small motor car where provision is 5 made for quickly removing the car from the tracks.

To this end I have provided a pair of extensible or slideable lifting handles, whereby the one end of the car may be easily 10 raised from the tracks by one or two men, and, by reason of the increased leverage thus obtained, the car will lend itself to easy handling.

The invention is more fully described in 15 the accompanying specification and fully illustrated in the drawings forming a part of this application.

In the drawings:—

Figure 1 is a plan view of a railway motor 20 car, more or less diagrammatically shown, with my improved extensible handles shown thereon.

Figure 2 is a detail view of one of the handles.

25 Figures 3, 4 and 5 represent the guide members for the handles.

The numeral 1 designates the frame and 30 2 the wheels of a railroad motor car, provided with the usual motor and transmission structures.

The numeral 5 designates the lifting handles, of which there are two, one at either side and projecting from one end of the car.

35 These handles are used when it is desired to lift the car from the track, and I have made the handles slideable or extensible, so that a very much increased leverage is obtained.

40 The handles are slideably mounted, each in a set of three guides members, 6, 7 and 9, located in alinement and secured to the frame of the car, so that each handle is slideable in its set of guides, and may be drawn

out from the inner position shown at A in 45 Figure 1, to the extreme extended position B.

The guide members are preferably made of sheet metal, bent to the form shown and provided with guide ways for the handles. 50

The handles are each provided with stop members 10 to limit the outward movement thereof, and each is provided with a metal strap 11 on its under side to prevent wear, the handle itself being preferably of wood. 55

It is evident that when it is desired to remove the car from the track, as is frequently necessary, it will not require four or more men to raise it from the track, but, when the handles 5 are withdrawn to their outermost position, the leverage is so increased that one or at most two men can raise the car, pivoting it on the wheels at the opposite end, and turning it until it can be drawn from the tracks. 65

When not in use, the handles are, of course, returned to housed position as shown at A.

Having thus fully described my invention, what I claim and desire to secure by Letters Patent is:—

1. In a railroad motor car, the combination of a set of wheels, a frame, two sets of handle guide members secured to the frame in alinement with each other, and a pair of 75 lifting handles, each formed with a stop at its extremity and a metal band on its lower side, slideably arranged in said guide members.

2. A lifting handle for railroad motor cars 80 comprising a handle member formed with a stop on its extremity to limit its movement in one direction, a metal sliding plate on its under side and a set of guide members attached to the frame of the car and 85 through which the handle slides.

In testimony whereof I affix my signature.
GEORGE J. ERMENTROUT.
